UNITED STATES PATENT OFFICE.

ROBERT P. PEARSON, OF GLOUCESTER CITY, NEW JERSEY, AND GEORGE O. DRAPER, OF HOPEDALE, MASSACHUSETTS, ASSIGNORS TO DRAPER COMPANY, OF PORTLAND, MAINE, AND HOPEDALE, MASSACHUSETTS.

LOOM-TEMPLE.

SPECIFICATION forming part of Letters Patent No. 687,543, dated November 26, 1901.

Application filed April 4, 1901. Serial No. 54,232. (No model.)

To all whom it may concern:

Be it known that we, ROBERT P. PEARSON, residing at Gloucester City, in the county of Camden and State of New Jersey, and GEORGE O. DRAPER, residing at Hopedale, in the county of Worcester and State of Massachusetts, citizens of the United States, have invented an Improvement in Loom-Temples, of which the following description, in connection with the accompanying drawings, is a specification, like letters on the drawings representing like parts.

This invention has for its object the production of a loom-temple embodying novel features of construction and arrangement whereby the temple is adapted to a great many different kinds of looms and to various styles of weaving.

Figure 1 is a side elevation of a loom-temple embodying one form of our invention, a portion of the breast-beam and the lay of a loom being shown in connection therewith; and Fig. 2 is a top or plan view of the temple illustrated in Fig. 1.

It is now common to attach loom-temples to the breast-beam of a loom by different plates, stands, or other devices in order to attain the proper position of the temple with relation to the lay, and in order to secure different adjustments various styles of plates are used. We have herein provided a loom-temple which by virtue of its novel features of construction obviates the use of the various attaching-plates or similar devices now in use, so that one temple can be adapted to various styles of weaving and to many different kinds of looms.

Referring to the drawings, the stand A, adapted to be secured to the breast-beam A⁴⁰, Fig. 1, and the slide-bar A' may be and are in the main of usual or well-known construction, but in accordance with our invention the temple-head is pivoted or hinged to the bar instead of being fixedly connected thereto. The pod B' is shown as provided with an upturned extension b, slotted at its upper end to form ears b', between which the end of the bar A' enters, as clearly shown in Fig. 2, and a headed pivot-stud a^x is extended

through the ears and the bar to hinge the head to the latter, the head comprising the pod B' and cap B³, which may be of usual construction. A nut a' screws onto the threaded end of the stud a^x, and when said nut is tightened the head will be held in fixed position relatively to the bar. It will be manifest that the head may be set in desired position relatively to the lay A³, Fig. 1, without changing the stand A, and in said figure we have shown in dotted lines another position of the head. We have also provided means for taking up the blow of the lay as it beats up independently of the head, so that when used in connection with the adjustable head the joint between the latter and the bar will not be subjected to the strain of the blow. In accordance with this part of our invention the bar A' has a depending leg a², terminating in a transverse laterally-extended foot a³, to which the heel B³ is secured by screws B⁴, passed through slots in the overhanging part b³ of the head and into threaded holes in the foot a³. The blow of the lay as it beats up is thus transmitted through the heel directly to the bar without any portion of the strain being imparted to the head or the joint between it and the bar, so that there is no tendency whatever to loosen the joint or disarrange the adjustment of the head. It will also be manifest that by this arrangement the angular position of the head may be adjusted as desired, whereas if the heel should be secured to or form a part of the head the heel would not be squarely engaged by the lay if the head should be adjusted at a considerable angle to the bar.

Inasmuch as the position of the temple-head relative to the lay can be varied or adjusted by our invention without change of the stand it will be manifest that the use of different forms of stands, plates, or other attaching devices are obviated and that one temple can be adapted to different kinds of looms and for various styles of weaving, as may be necessary.

Having described our invention, what we claim as new, and desire to secure by Letters Patent, is—

1. In a loom-temple, a bar, a depending heel rigidly secured thereto, a head pivotally mounted on the bar to swing in a vertical path relative to the bar, and means to maintain the head in vertically-adjusted position relative to the bar.
2. In a loom-temple, the stand, a bar longitudinally movable therein, the head, a transverse pivot connecting it with the bar where-
to by the head may be swung in a vertical path, and means to hold the head from pivotal movement.

In testimony whereof we have signed our names to this specification in the presence of two subscribing witnesses.

ROBERT P. PEARSON.
GEORGE O. DRAPER.
